UNITED STATES PATENT OFFICE.

COLIN ALLERTON, OF WEST HOMESTEAD, PENNSYLVANIA.

RAILROAD-TIE.

1,078,596.

Specification of Letters Patent.

Patented Nov. 11, 1913.

Application filed July 5, 1911, Serial No. 636,985. Renewed August 16, 1913. Serial No. 785,123.

To all whom it may concern:

Be it known that I, COLIN ALLERTON, a citizen of the United States, residing at West Homestead, in the county of Allegheny and State of Pennsylvania, have invented certain new and useful Improvements in Railroad-Ties, of which the following is a specification.

This invention relates to improvements 10 in railroad ties and the distinctive feature consists in providing a form of tie or joint for the rails which is adapted to be held in rigid contact therewith without the use of rivets, tie bolts or similar fastening means.

One of the objects of my invention is to 15 provide a rigid joint for rails embracing the minimum number of parts, that may readily be assembled and dismantled and when assembled will expose above the support for the rails but two elements each 20 clamping the opposite flange of the rail, thereby simplifying the structure and reducing the cost of manufacture.

With these and other objects in view, my 25 invention consists in the combination and arrangement of structural elements herein-after described, shown in the drawings and then more particularly pointed out in the appended claims.

Referring to the drawings, Figure 1 is a 30 side elevation, partly in section, of my railroad tie, Fig. 2 is a top plan view thereof, showing the recess in which are disposed the clamping parts, Fig. 3 is an end elevation 35 in section, of the base or support for the rails forming part of my invention taken on the line X—X in Fig. 2 and Fig. 4 is a top plan view in detail of the clamp element 5 on the line Y—Y of Fig. 2.

In the drawings wherein similar reference 40 characters designate similar parts 1 is a longitudinal base or support preferably made of steel upon which the rails 4 are fastened by the clamps 5 and their accessories. The 45 base is formed preferably trapezoidal in form as shown in Fig. 3 and upon the upper surface at opposite ends, a longitudinal recess is formed having transversely extending terminal branches 2^a and 2^b respectively 50 disposed at opposite sides with respect to the median line of the recess. The sides 2^a having the recess between them are formed at opposite points with recesses 3 of lesser depth than the longitudinal recess 2 within

55 which the rails snugly fit as shown in Fig. 2, it being understood that for curves in the

rails, the curves in the recesses will be correspondingly trueed. 5 are the clamping members and comprise each a flat base 6, which fits snugly into the recesses 2 at each 60 end of the support 1 and each side of the rails 4. The top surface of the clamping member 5 is formed with outwardly projecting portions 7 and 8 at opposite sides which are suitably spaced apart from the base 6 to form in the one case a recess adapted to embrace one flange of a rail and in the other case, a substantially rectangular recess whose top edge is flush with the top of the base 1. In operation the rails 4 are fitted 65 within the recesses 3 and the base of a clamp 5 fitted with the recess or track 2 at opposite sides of the rail and both clamp members are then slid until the portions 6^a underlie the rail 4 and the opposite extensions 6^a are flat upon the support 3. Metallic 70 slabs 9, preferably also of steel and of the same thickness as the base 6 of the clamps 5, being shaped to snugly fit the remaining aliquot part of the track or recess 2 are then 75 stamped or otherwise mounted in position within the recess 5 alongside the clamp 5, the edges of the slabs 9 and clamps 8 being suitably finished so that the cheeks 6^b and 7 of the clamps 5 will bind against the 80 opposite flanges of the rail. To complete 85 the joint or tie additional slabs 10 shaped to snugly fit the uncovered portions of the recesses 2 are interposed between the shoulders formed by the support 1 and the clamp 90 5 so that the slabs 10 will completely overlie the slabs 9 and extensions 6^a of the said clamps and thus continue the flush surface 95 of the support 1. By this arrangement a positively acting joint is formed in a very 95 attractive manner since only the elements 5 will project above the surface of said support. The branch recesses 2^a and 2^b at each 100 end of the support are for facilitating the insertion of appropriate tools wherewith to 100 remove or disengage the slabs and thereby release the clamps and remove the rails.

My tie may be constructed of metal, concrete, wood or other desirable material.

I claim and desire to secure by Letters 105 Patent:—

1. A railroad tie having a longitudinal recess therein, two shoes, each shoe being formed at opposite sides with spaced outwardly-extending portions whereby recesses 110 are provided, said shoes having their bases fitted in said longitudinal recess and receiv-

- ing the flanges of a rail in the recesses of one side, metallic slabs fitted in the ends of said longitudinal recess and each jamming one shoe against said rail, and a metallic slab 5 fitted in each end of said longitudinal recess and in the other recess of the adjacent shoe, said last-named slabs each overlying one of the first-named slabs and jamming the shoe against the rail.
- 10 2. A metallic railroad tie having a longitudinal recess, said recess formed at diagonally-opposite ends with transverse extensions opening into the sides of said tie, two metallic shoes each formed at one side with
- 15 a flange-receiving part, a flat base formed on each shoe being fitted in said recess, said bases forming a seat for a rail when said shoes engage the flanges of said rail, metal-

lic slabs fitted at the ends of said recess and resting on the bottom thereof, said slabs 20 jamming the bases of said shoes to cause them to hold the rail, each of said shoes formed with a recess, and slabs overlying said first-named slabs and fitted in said longitudinal recess and in the recesses of said 25 shoes, said first and second-named slabs being of uniform width with said longitudinal recess and arranged to jam said shoes against the rail.

In testimony whereof I affix my signature 30 in presence of two witnesses.

COLIN ALLERTON.
